STEAM BOILER

Andrew McKee, deceased, late of Ossining, N. Y.,
by Charlotte Nelson Anderson, administratrix,
Ossining, N. Y.

Application July 13, 1934, Serial No. 734,888

5 Claims. (Cl. 122—268)

This invention relates to certain improvements in steam-boilers in which a plurality of double heating tubes are employed and spaced apart one within the other to provide annular water spaces on opposite sides of which heat is applied by adjacent tubular walls.

The objects of the invention include means for arranging the heating tubes with respect to their lengths to afford relatively increased travel of 10 the heated gases in the interest of efficiency.

A further object is to provide means for distributing the heated gases over the superficial length of the outer heating tubes.

Also, means for effecting a localized heating 15 action in a certain portion of the boiler.

Also, to provide for the boiler a fire-box extension having side water-walls connected with and forming part of the boiler-water circulation.

Also, to provide for the fire-box a series of 20 fresh-air inlets adapted to supply air heated by the circulation of the hot water contained in the fire-box water-walls.

Also, to provide heating means for an auxiliary water heater disposed within the boiler.

For further comprehension of the invention, and of the objects and advantages thereof, reference is had to the following description and accompanying drawing, and to the appended claims in which the various features of the invention are 25 more particularly pointed out.

Referring to the drawing in which similar characters of reference designate like parts throughout the several views:

Figure 1 is a sectional side elevational view of 30 a boiler embodying my invention.

Figure 2 is a front elevational view, showing a portion of the boiler front removed to more clearly illustrate both the interior and exterior of the boiler.

Figure 3 is a rear elevational view of the boiler 35 shown partially in section.

Figure 4 is an enlarged sectional detail view showing the connections between the water-legs and the double heating tubes.

In the drawing, numerals 10 designate the ash-pit base of the boiler having the usual ash-door 11, and the upper flanges 12 which support the grate-bars 13, and above the latter the boiler is provided with a forwardly extending fire-box 14 having a rear bridge-wall 15. The front and side walls of the fire-box, indicated respectively in full and dotted lines by 16 and 17, constitute water-walls, the front wall thereof being formed with a pair of fire-door openings 18. Extending 50 above the side water-walls 17 are the opposite

main side walls 17a of the boiler, and disposed between the opposite ends of the latter are a pair of front and rear water-legs 19 and 20 spaced apart from each other in parallel relation and pitched at their upper ends toward the rear of the boiler. As thus positioned the water-legs 5 form between the opposite end walls of the boiler, front, rear and intermediate transverse flue sections adapted to pass the heated gases. In construction the water-legs comprise inner and outer tube sheets 21 and 22 secured together in spaced relation to provide water and steam passages 19a and 20a.

Connecting the opposite water-legs together, and arranged in upper and lower series, are a 15 plurality of double heating tubes 24 and 25 disposed one within the other in spaced relation to provide annular water and steam passages 26 therebetween which communicate with the passages 19a and 20a of the water-legs, the opposite 20 ends of the outer and inner tubes being respectively jointed to the tube-sheets 21 and 22, as indicated in Fig. 4, the inner tubes 25 being enlarged at the front ends 22a to provide means 25 whereby the several tube ends may be readily expanded into corresponding perforations in their respective tube-sheets, and also to afford means for conveniently renewing defective tubes by the insertion of the outer tubes through the perforations of the enlarged ends in the usual manner. 30

Leading into the lower end of the rear water-leg 20 are a plurality of boiler-water circulating pipes 27, and leading from the upper end of front water-leg 19 are a plurality of horizontal steam and water tubes 28 connected to the steam and 35 water drum 29, and from which latter descend the vertical circulating pipes 30 that lead into the hot-water chamber 31 which in turn leads through pipes 32 to the circulating pipes 27, thus forming a complete circuit for the boiler-water 40 and steam that operate through the double heating tubes to afford a continuous and rapid circulation under the influence of a moderate degree of heat from gases of combustion.

For confining the flow of hot gases above the 45 grate-bars a base wall 33 is provided and formed with a transverse foundation wall 34 for supporting the rear water-leg 20, the base wall being also joined to the rear end wall 35 which in turn is joined to the steam and water drum 29, the latter being also joined to the top wall 36, which also in turn connects the front door-frame 37 and the opposite upper extensions of the side walls 17a. Hingedly secured to the door-frame 37 are 50 a pair of doors 38 arranged to be opened and 55

closed and adapted in conjunction with the front water-leg to form the front flue 45 for the passage of the gases.

A top wall 39 is also provided for the fire-box 5 extension 14 and is carried by a row of double tubes 40 and 41 spaced apart one within the other to leave an annular water and steam space therebetween, the opposite ends of the larger tubes 40 being connected to the opposite walls that include 10 the bottom portion of the tube-sheet 22 of water-leg 19 and the inner wall of the front water-wall 16, whereby steam and water connection is provided between said water-leg and the communicating front and side water-walls of the fire-box, 15 while the inner tubes 41 are secured at their inner ends to the inner tube-sheet 21 of the water-leg 19 and their outer ends to the outer wall of the water-wall 16, the smaller tubes being spaced centrally of the larger ones and serving as inlets 20 to admit heated fresh air into the fire-box to increase combustion therein, and also acting to absorb a portion of heat from the boiler-water circulation.

Within and closely secured between its opposite side walls the boiler is provided with a horizontal division plate 42 that extends rearwardly from the rear water-leg 20 to the rear wall of the boiler and serves to divide the double heating tubes 24 and 25 into upper and lower series with respect 25 to the flow of gases through the inner tubes 25, and to form upper and lower rear flue sections 43a and 44 respectively aligned with the upper and lower series of the inner heating tubes for the passage of hot gases. From the fire-box 14 the 30 gases flow upwardly through the intermediate flue 43 between and around the exterior surfaces of the outer heating tubes 24 to the upper portion of said flue, thence rearwardly and downwardly over the top of the rear water-leg 20 to react 35 against the division plate and forcibly impinge and effect a localized heating action against the upper surface of the division plate and against the cylindrical outer surfaces of the steam drum 29 and the hot-water chamber 31 whereby the 40 accumulation of the gases serve to superheat the several contacting parts. From the division plate the gases flow forwardly through the upper series 45 of inner tubes 25 and into the front flue 45 from which they pass downwardly and rearwardly 45 through the lower series of inner tubes to the lower rear flue section 44 disposed below said division plate 42, and from which lower flue section the spent gases are discharged through the smoke flue 46 of the rear boiler-wall 35.

55 At the upper end of the water-leg 19 and extending transversely therethrough is a row of tubes 47 forming gas passages leading between the front flue 45 and the intermediate flue 43 that acts to deflect a portion of the gases from the 60 latter flue into the former and thus tend to equalize the flow and heating effect of the gases over the lengths of the heating tubes.

Supported exteriorly of the boiler is indicated a house radiator 48 having a steam supply pipe 65 49 leading from the boiler and a drain or feed-water pipe 50 discharging back into the boiler through the circulating pipe 27, the latter being arranged in connection with the relatively smaller pipe 32 to form an injector nozzle, shown in dotted lines, actuated by the velocity of the boiler water to create a suction on the drain pipe 50.

As herein shown the hot-water chamber 31, forming a part of the boiler-water circulating system, is provided with a header 51 projecting 70 exteriorly of the boiler and formed with a pair 75

of separate compartments having outer pipe connections 51a and 51b that communicate through the compartments to the opposite ends of the auxiliary water-heating coil 52, shown in dotted lines within the chamber. The opposite ends of the outer pipes 51a and 51b are connected to the water-storage tank 53 in the usual manner, as are also the respective cold-water supply and hot-water discharge pipes 53a and 53b.

5 A relatively free passage of the heated gases 10 at the upper end of the intermediate flue into the rear upper flue section 43a of the boiler is provided by the inclination of the upper row of heating tubes with respect to the top wall of the boiler which affords a gradually increasing flue 15 area from the front to the rear water-legs to substantially insure a collection of gases that serve to superheat the water circulation in its passage through the rear upper flue section.

The hot-water chamber 31 forming a casing for 20 the auxiliary heater coil 52 is disposed adjacent the upper surface of the division plate 42 and within the direct range of the path of the hot gases that tend to build up at this point a relatively concentrated heating condition that has 25 the effect of more rapidly heating and retaining the same in the added heater than would occur in ordinary conditions without the aid of said division plate. And also by the use of the latter, the path of travel of the hot gases around and 30 through the heating tubes may be largely increased with a corresponding increase in heating surface.

What is claimed is:

1. In a steam-boiler, a fire-box, a plurality of 35 double heating tubes arranged one within the other in upper and lower series, front and rear water-leg connections secured to the opposite ends of said heating tubes and disposed between the opposite end walls of the boiler to form front, 40 rear and intermediate transverse flues, a division plate disposed within said rear flue to form upper and lower rear flue sections respectively aligned with the upper and lower series of inner heating tubes, the said lower flue section having a smoke 45 flue, whereby the heated gases from the fire-box pass upwardly through the intermediate flue, between the front and rear water-legs and around and between the outer surfaces of the upper and lower series of outer heating tubes, thence rearwardly and downwardly through the rear upper flue section to engage as a stop said division plate, thence forwardly through the upper series of 50 inner heating tubes to the front flue, thence downwardly therefrom and rearwardly through the lower series of inner heating tubes to the rear lower flue section where it escapes through the smoke flue thereof.

2. In a steam boiler, a plurality of double heating tubes arranged one within the other in upper and lower series, front and rear water-leg connections secured to the opposite ends of said heating tubes and disposed between the opposite end walls of said boiler to form front, rear and intermediate transverse flues, tubular passages communicating between the front and intermediate flues at the upper end of said front water-leg, and a division plate disposed within said rear flue to form upper and lower rear flue sections respectively aligned with the upper and lower 70 series of inner heating tubes, and effect the passage of the products of combustion.

3. In a steam-boiler, water-heating tubes having front and rear water-leg connections, a fire-box having an extension projecting forwardly 75

of said boiler and provided with side and front water-walls communicating with said water-legs, a top wall for said extension, means for supporting said top wall consisting of a plurality of water tubes carried at opposite ends by said front water-leg and front water-wall in water connection therewith, and air tubes extending through said water tubes and supported at opposite ends by said front water-leg and front water-wall and adapted to supply heated fresh air to said firebox.

4. In a steam-boiler, a plurality of double heating tubes arranged one within the other in upper and lower series, front and rear water-leg connections secured to the opposite ends of said heating tubes and disposed between the opposite end walls of said boiler to form front, rear and intermediate transverse flues, a division plate disposed within said rear flue to form upper and lower flue sections respectively aligned with the upper and lower series of inner heating tubes and effect a localized heating action adjacent the upper surface of said division plate means forming a steam and water circulation within said boiler including a hot-water chamber enclosed in said rear upper flue adjacent said division plate, and an auxiliary water-heating coil disposed

within said hot-water chamber, and water inlet and outlet connections for said coil extending outwardly of said boiler.

5. In a steam-boiler, a plurality of double heating tubes arranged one within the other in upper and lower series, front and rear water-leg connections secured to the opposite ends of said tubes and disposed between the opposite end walls of the boiler to form front, rear and intermediate transverse flues, a division plate disposed within said rear flue to form upper and lower rear flue sections respectively aligned with the upper and lower series of inner heating tubes, one or more gas passages extending transversely through said front water-leg at the upper end thereof, said flues being adapted to receive the hot gases of the fire-box of the boiler and upwardly pass the same through said intermediate flue between said front and rear water-legs and around and between said outer heating tubes and distribute through the gas passages of the front water-leg to the front flue and from the intermediate flue rearwardly over the rear water-leg to the rear upper flue section and division plate.
